US0D1082851S

(12) **United States Design Patent** (10) **Patent No.:** **US D1,082,851 S**
(45) **Date of Patent:** **** Jul. 8, 2025**

(54) **DISPLAY SCREEN OR PORTION THEREOF WITH ICON**

(71) Applicant: **Getac Technology Corporation**, New Taipei (TW)

(72) Inventor: **Wan-Hua Tsai**, Taipei (TW)

(73) Assignee: **Getac Technology Corporation**, New Taipei (TW)

(**) Term: **15 Years**

(21) Appl. No.: **29/860,023**

(22) Filed: **Nov. 15, 2022**

(51) **LOC (15) Cl.** **14-04**

(52) **U.S. Cl.**

USPC **D14/492**

(57) **CLAIM**

The ornamental design for a display screen or portion thereof with icon as shown and described.

DESCRIPTION

FIGURE is a front view of a first embodiment of a display screen or portion thereof with icon showing the new design. The dot-dash broken lines in the FIGURE illustrate boundary lines and form no part of the claimed design. The dot-dot-dash broken lines show the display screen or portion thereof and form no part of the claimed design. The other broken lines in the drawing illustrate portions of the article and form no part of the claimed design.

1 Claim, 1 Drawing Sheet
